CLAIM

The ornamental design for a soundbar, as shown and described.

DESCRIPTION

FIG. 1 shows a top front right perspective view of a soundbar.

FIG. 2 shows a bottom front left perspective view thereof.

FIG. 3 shows a front view thereof.

FIG. 4 shows a rear view thereof.

FIG. 5 shows a left side view thereof.

FIG. 6 shows a right side view thereof.

FIG. 7 shows a top view thereof.

FIG. 8 shows a bottom view thereof.

FIG. 9 is an exploded view of a portion of FIG. 4.

FIG. 10 is an exploded view of a portion of FIG. 7; and,

FIG. 11 is an exploded view of a portion of FIG. 8.

Any broken line shown in the drawing figures are for illustrative purposes only and form no part of claimed design.

1 Claim, 11 Drawing Sheets
